(57) **CLAIM**

The ornamental design for a tire, as shown and described.

DESCRIPTION

FIG. 1 is a front perspective view of a tire;
FIG. 2 is a side perspective view thereof;
FIG. 3 is a front elevation view thereof;
FIG. 4 is a side elevation view thereof; and,
FIG. 5 is an enlarged, detailed view of a shoulder-portion thereof.

The broken lines are included for the purpose of illustrating portions of the tire that form no part of the claimed design.
